TOOL AND METHOD OF MAKING SAME

Malcolm G. Kreag, West Los Angeles, Calif., assignor, by mesne assignments, to Union Carbide and Carbon Corporation, a corporation of New York

Application September 15, 1932, Serial No. 633,232

17 Claims. (Cl. 76—108)

This invention relates to implements or tools and to the method of making the same. The invention is more particularly applicable to the construction of such implements or tools as are used for impact drilling, digging or breaking up hard formations, such as rock drills, bucket teeth for use in excavating, and gads for breaking up concrete and certain rock formations.

The invention will be herein illustrated and described more particularly in its application to gads although it is to be clearly understood that features of the invention are applicable to all manner of implements or tools wherein a durable cutting or drilling point or edge is desired.

Gads and other tools of the above character are ordinarily made of high carbon tool steel and are provided with a pointed end or sharp edge according to the nature of the tool. Before use, the sharp points or edges are tempered by quenching in water to increase their lasting qualities, and points so treated last in use anywhere from five minutes to five hours depending upon the nature of the formation to be broken up thereby and upon the degree of hardness to which the points have been tempered. It is highly desirable that a sharpened point be dependable for use over a reasonably long period of time in order that too much of the workman's time may not be consumed in tool dressing and in order that the cost of maintenance may not be disproportionate to the work accomplished with the tool. The quality of a tempering job is a matter of hazard depending on the skill of the workman and upon other factors beyond his control. A high degree of skill is required if satisfactory results are to be obtained and an ordinary workman is seldom sufficiently skilled to perform the operation with any assurance of a reliable product; the operation being in fact, a blacksmith's job requiring shop facilities.

Gads are comparatively expensive tools, costing at the present market prices four or five dollars each, and, as heretofore constructed, wear out rapidly and require frequent and expensive redressing and retempering to keep them sharp, besides consuming considerable time and energy and entailing other inconveniences to a workman operating therewith.

In attempting to solve the above problems and provide tools which will stand up under long use without necessity of redressing or repair, it has been proposed to cap the tip end or edge of tools with a layer of hard wear-resisting material, preferably welded thereto. Such a construction, while giving better results than a tempered tool,

is far from satisfactory inasmuch as the steel under the cap has a tendency to mushroom, forcing the cap to spall off before it has a chance to do any considerable amount of work. I have been able also to get quite good results with gads by providing the tip of their pointed ends of durable wear-resisting material. A tool so tipped, while having wear-resisting qualities in the ratio of from three to five to one over those with tempered points, still leaves much to be desired in that it necessitates frequent "Stellitizing" requiring considerable skill and therefore tending to discourage its use. No satisfactory substitute for the tempered tool heretofore used has to my knowledge been provided prior to my invention which lends itself to simple and inexpensive manufacture and maintenance operations that may be performed by a comparatively unskilled workman.

It is desirable, therefore, and an important object of this invention to provide an improved construction in implements and tools of the above character, which will stand up under long usage without redressing, resharpening or other maintenance operations; which will require little or no skill in redressing and resharpening; which will have a long life and will not require frequent replacement; which will be largely self-sharpening; and will lend itself to a simple and inexpensive process of manufacture.

A further important object of the invention is to provide an improved and simple process of manufacture by which implements or tools of the above character and desirable qualities may be inexpensively manufactured without any considerable requirements of skill on the part of the manufacturer and without any special facilities for carrying out the process.

In the broad aspect of the invention, the implement or tool may comprise a supporting shank or body of strong, tough metal having its effective working point or edge of a hard wear-resisting metallic substance projecting beyond the shank or body and bonded thereto, as by welding. Preferably this point or edge is a part of a core extending a considerable depth into the shank or body by which it is surrounded, and is supported on all sides by the body to which it is suitably bonded, as by being welded thereto on all sides and throughout its entire length except the protruding point or edge. The shank or body of the tool, while strong and tough, may be of soft, readily abradable metal so as to adapt the tool to be sharpened by grinding back the shank or body when the tool be-

comes dull. For convenience of manufacture, the shank or body may be provided with a longitudinally extending groove, in the bottom of which, the core is placed and this groove may 5 be closed in behind the core in any suitable manner as by filling the same with a suitable material similar in its qualities to those of the shank or body.

A suitable process of manufacture, whereby 10 implements or tools of the above character may be conveniently and inexpensively made, consists in providing a piece of suitable material, as high carbon tool steel, forming a recess or groove therein extending from one end or edge, as the 15 case may be, back a considerable distance into the shank or body thereof and providing a core of hard wear-resisting metal in the recess or groove which is preferably welded to the bottom and sides thereof so as to form a bond between 20 the core and supporting metal throughout the length of the core and, in the completed article, on all sides thereof. After bonding the core to the bottom and sides of the groove or recess, the latter may be closed behind the core as by 25 filling in with material similar in quality to the body in molten state so as to completely encase the core; the filling material being preferably welded to the core and sides of the recess or groove, progressively, as it is deposited. The 30 implement or tool may then be heat treated to refine the grain and remove crystalline structure so that the bond between the metal of the core and the supporting body may the better withstand shock and the shank or body may 35 be shaped to a point or edge and sharpened so as to expose the core in a sharp point or edge as the case may be.

The above and other objects and novel features of the invention will become apparent from 40 the following specifications taken with the accompanying drawing, in which

Fig. 1 is a view in side elevation of a gad made in accordance with the present invention.

Fig. 2 is a fragmentary view on an enlarged 45 scale compared with Fig. 1 showing a portion of the gad at its pointed end in longitudinal section.

Fig. 3 is a cross-sectional view on the same scale as Fig. 2, and on line 3—3, Fig. 1.

The invention is shown in the drawing as 50 applied to a gad which may be used with rock drills or on the end of a bar or staff. This tool comprises a shank 10 which may be provided with the usual collar 11 formed integrally 55 therewith. One end of the shank is drawn to a point, as at 12, and the shank may be provided at this end with a recess or groove 13 extending from the tip end longitudinally of the shank rearwardly thereof a suitable distance, for example, about three or four inches with gads of 60 standard construction. The side walls of the groove may diverge toward the outer side walls of the shank, as illustrated in Fig. 3.

The groove or recess is preferably of a depth 65 sufficiently greater than the radial dimension of the shank to position a core 14 placed in the bottom thereof coaxially of the shank although it may also, with good effect, be placed eccentric to said axis with certain types of tools. The core is desirably of a hard material more 70 wear resisting than the supporting steel, as "Haynes Stellite", a non-ferrous alloy including as its principal ingredients tungsten, cobalt and chromium as described in the patents to 75 Elwood Haynes Nos. 873,745; 1,057,423; 1,057,

828; and 1,150,113. The core is preferably welded to the bottom of the groove throughout its length and is supported on all sides by the metal of the shank, preferably of high carbon tool steel which is strong and tough while, at 5 the same time, being sufficiently soft to be readily abradable in sharpening the tool and, under some conditions of work and, with certain types of tools to which the invention may be applied, being substantially self-sharpening. The groove 10 or recess is closed back of the core in any suitable manner as by depositing a filler 15 of suitable material therein; the filler material preferably having qualities similar to those of the shank so as to provide substantially the same 15 character of support and the same qualities as to abradability on all sides of the core. The 20 filler material is, therefore, desirably a tough ductile substance such as "Hascrome", an alloy having iron, chromium, and manganese as its chief ingredients as set forth in the patent to Frederick M. Becket, 1,333,151, which is welded to the core 14 and to the shank 10 along the 25 walls of the groove or recess. "Hascrome" lends itself admirably to the needs of the present 30 situation since in addition to possessing the above desirable qualities of toughness and ductility it bonds readily both with the steel of the shank and the "Stellite" of the core. Other materials, however, as high carbon steel such as 35 that of the shank may be used with excellent results.

In the manufacture of tools of this character I may take a bar of suitable metal, as high carbon tool steel and form a longitudinal recess or 35 groove therein, such as the groove 13 referred to above, at one end. This groove may be formed in any suitable manner as by milling or drop forging, either of which methods is simple and requires little skill on the part of the workman. 40 The core may then be placed in the bottom of the groove and welded thereto throughout its length. To this end, the core may be preformed and placed in the groove as a unit but a preferable method is to deposit the core in place by 45 a welding process in which the metal of the core is melted from a rod as in certain welding processes and is progressively bonded to the bottom of the groove as it is deposited, the groove being maintained the while at the point of deposit at welding temperature and in condition to bond with the metal of the core. The welding process whereby metal is welded to a base by melting the former and flowing it onto the latter so as to bond therewith is herein referred 50 to as weld-depositing.

A core of the desired thickness having been deposited and welded in place in this manner, the groove is closed back of it in any suitable manner as by filling in with a metal of similar 55 character to that of the shank. A convenient metallic substance for this purpose is "Hascrome" referred to above, which is obtainable on the market in the form of welding bars and may be readily melted into the groove to fill 60 the same. This material as stated above bonds readily with other metals, both the steel of the shank and the "Stellite" of the core, and is soft and ductile while being at the same time 65 strong and tough. It is desirable that the core have a welded bond on all sides and throughout 70 its length of contact with the shank and filler, so that it will be firmly supported against breakage by impact shock. To this end, the "Hascrome" is preferably welded to the core and to 75

the sides of the groove by weld-depositing the same in the groove, and the tool is afterwards heat treated in order to refine the grain of the steel. The cored end of the shank may then 5 be ground to a point to expose the end of the core whereupon the tool is ready for use. Thus, the tool may be provided with a pointed substantially conical end in which the major portion 10 of the core is of substantially uniform cross section and is reinforced by the enclosing body portion of substantially uniform thickness 15 on all sides of the core.

The end of the tool may be resharpened when it becomes dull so long as there remains sufficient core in the shank; and a gad of standard 15 dimensions having a core three or four inches long will stand about twenty-five or thirty sharpenings. In sharpening the tool, it is only necessary to grind away the supporting material 20 so as to expose the end of the core and to bring the core to a suitable point which is a simple operation requiring little skill and may be performed at a trifling expense as compared with tempering. Under certain conditions, a tool 25 made in accordance with the invention is substantially self-sharpening as in excavation bucket teeth and other situations where the tool digs into the hard surface it is intended to break up.

30 A gad in accordance with this invention will have a life equal to about five gads tempered according to previously known methods. These five gads would require a total of one hundred and fifty expensive redressings in the course 35 of their combined life as compared with the twenty-five or thirty resharpenings for the gad of my invention. My gad is therefore materially less expensive both as to initial cost and maintenance than a tempered gad besides being more 40 economical of the operator's time which is no inconsiderable factor in the course of a piece of work being performed thereby.

45 By the term "weld deposit" used hereinafter in the claims I mean the flowing of metal into the groove so as to form a welded bond between the same and the surface of the groove.

I claim:

1. As an article of manufacture, an implement or tool for drilling or for breaking up 50 hard formations by impact, the same having an elongated body of tough abradable material; and an elongated core of a material of greater wear-resistance than that of the said body, the core being disposed longitudinally of the body and completely encased by the body throughout at 55 least the major portion of its length; said core having an end protruding from an end of the body, and the portion of the body adjacent the protruding end of the core being tapered on all sides along lines converging to a point.

60 2. An implement or tool for drilling or for breaking up hard formations by impact; comprising a body of metallic material having a longitudinal groove; a metallic core in the bottom of the groove positioned coaxially with the body and partly filling the groove; and a metallic 65 filler in the groove above the core completing the filling thereof.

70 3. An implement or tool for drilling or for breaking up hard formations by impact; comprising a body of comparatively soft, tough, metallic material having a longitudinal groove; a metallic core in the bottom of the groove positioned coaxially with the body; and a metallic 75

filler of comparatively soft but tough metallic material in the groove on top of the core.

4. An implement or tool for use in drilling or breaking up hard formations by impact, comprising an elongated body of metallic material 5 having a longitudinal groove; a metallic core in the bottom of the groove positioned along the longitudinal axis of the body and positioned entirely within the groove throughout at least the major portion of its length; said core being 10 welded to the walls of the body at the groove substantially throughout the length of the core; and a metallic material sealing the groove on top of the core.

5. An implement or tool for drilling or for 15 breaking up hard formations by impact; comprising an elongated body of metallic material having a longitudinal groove; a layer of wear-resisting metallic material welded to the bottom of the groove; and a filler of metal in the 20 groove welded to the sides thereof and together with the body completely surrounding the core; the layer of wear-resisting material being arranged coaxially with the body.

6. The method of making a tool or implement 25 which consists in forming a groove in a metallic body; weld-depositing a core therein; and placing a filler in the groove weld-deposited to the sides of the groove; said core and body being 30 coaxially arranged.

7. The method of making a tool or implement which consists in forming a groove in a metallic body; weld-depositing a core therein so as to lie coaxially with the body and so as to weld it to the sides and bottom of the 35 groove; and closing the groove so as to encase the core on all sides.

8. The method of making a tool or implement which consists in forming a lateral groove in 40 an elongated metallic body so as to extend from the cutting edge or point of the tool back into the body a substantial distance; welding a core therein so as to lie coaxially with the body and so as to weld it to the sides and bottom of the groove; and closing the groove so as to encase 45 the core on all sides.

9. A method of making an implement or tool having an axial core of wear-resistant metal and an elongated body of strong metal relatively softer and less wear-resistant than said core and permanently secured to, enclosing, and uniformly reinforcing the major portion of said core, said method comprising forming a groove in the side of the body lengthwise of the longitudinal axis thereof and of such depth that said axis will lie within said groove; inserting the core of wear-resistant metal in said groove, the core being at least as long as the groove and its longitudinal axis substantially coinciding with that of the body; and weld-depositing sufficient metal into and along said groove and onto said core to fill the groove and to permanently unite the body, the core, and the added metal.

10. The method of making an implement or tool of durable quality which consists in providing a body of metallic material; forming a groove longitudinally thereof and of a depth greater than one-half of the dimension of the body perpendicular to its longitudinal axis; placing a metallic core in the bottom of the groove 70 so as to be coaxial with the body; and closing the groove by welding a metallic filler around the core.

11. The method of making an implement or tool of durable quality which consists in pro- 75

- viding an elongated body of metallic material; forming a groove longitudinally thereof and of a depth greater than one-half of the dimension of the body perpendicular to its longitudinal axis; placing a metallic core in the bottom of the groove; welding the core in the bottom of the groove; weld-depositing a metallic filler into the groove on top of the core and heat treating the tool.
10. 12. The method of making an implement or tool of durable quality which consists in providing a rigid elongated body of metallic material; forming a groove longitudinally thereof and of a depth greater than one-half of the dimension of the body perpendicular to its longitudinal axis; placing a metallic core in the bottom of the groove; welding said core in the bottom of the groove; and closing the groove back of the core with metal weld deposited into the groove so as to be bound with the core and sides of the groove throughout the extent of the core.
13. The method of making an implement or tool of durable quality which consists in providing a rigid elongated body of metallic material; forming a groove longitudinally thereof and of a depth greater than one-half of the dimension of the body perpendicular to its longitudinal axis; welding a core in the bottom of the groove; closing the groove back of the core by weld depositing metal into the groove so as to bond with the sides thereof and with the core throughout the entire extent of surfaces with which the weld deposited metal contacts; and heat treating the tool.
14. The method of making an implement adapted for drilling or breaking up hard formations, which comprises forming a longitudinal groove within an elongated body of at least approximately uniform transverse cross-section formed of tough, readily-abradable metal, the said groove extending at least to the longitudinal axis of the body, weld-depositing a core of molten, hard, wear-resistant metal within the lower portion of the groove, thereafter filling the remainder of the groove above the said core with a molten body of relatively-soft, tough, ductile metal, thereby welding the same to the core and to the first-named body along their respective surfaces of contact.
15. The method of making an implement adapted for drilling or breaking up hard formations, which comprises forming a longitudinal groove within an elongated body of at least approximately uniform transverse cross-section formed of tough, readily-abradable metal, the said groove extending at least to the longitudinal axis of the body, weld-depositing a core of molten, hard, wear-resistant metal within the lower portion of the groove, thereafter filling the remainder of the groove above the said core with a molten body of relatively-soft, tough, ductile metal, thereby welding the same to the core and to the first-named body along their respective surfaces of contact, heat-treating the resultant composite structure, and tapering the latter at one end to form an implement having a point and to expose an end of the core.
16. An implement or tool comprising a body of tough, abradable, metallic material having a longitudinal groove; a core of metallic material of greater wear-resistance than that of said body weld-deposited into said groove and partly filling the same; and tough, abradable, metallic material on top of said core secured within said groove and substantially completing the filling thereof.
17. An implement or tool having a pointed end and comprising a body of comparatively tough, abradable metal having a groove; a core of metal of greater wear-resistance than that of said body permanently secured within said groove, said body and core having coinciding longitudinal axes; a relatively thick filler of metal in said groove on top of said core and permanently secured to said body so that said core is uniformly supported on all sides over the major portion of its length; and an end of said core projecting from an end of said body and being pointed to constitute the pointed end of said implement, the exterior surface of said pointed end merging into the adjoining surface of said body.

MALCOLM G. KREAG.
